CRANK MOVEMENT ELIMINATING DEAD CENTER

Amel B. Broluska, Detroit, Mich.

Application November 7, 1938, Serial No. 239,239

7 Claims. (Cl. 74—36)

My invention relates to crank movements for use in machines of all kinds in which a reciprocatory motion is converted into a rotary one, and more particularly adapted for such movements in which the useful work is applied to the rotary element during travel of the reciprocatory element in one direction only.

The principal object of my said invention is to provide a movement of the character referred to in which the dead-center effect common to ordinary crank movements is eliminated at the commencement of the working or power stroke, so that the dynamic force of the reciprocatory element is transmitted more effectively to the rotary element, thereby reducing frictional losses and economising the available power.

Such an object is particularly desirable in the case of pedal-operated devices such as printing machines, sewing machines, and especially in bicycles which have again become an important feature of the national life, and are being manufactured and sold in increasingly large numbers. Its importance as applied to machines of the class just recited is particularly great on account of the saving of human power and the reduction of personal fatigue, enabling the operator to concentrate his attention on the work being done, and in the case of bicycles to better enjoy the healthy exercise and the contemplation of the surrounding scenery.

It is contemplated, however that my improved crank movement will be found equally advantageous when used in prime movers such as gas and gasoline engines, Diesel engines and steam engines, as applied to the propulsion of automobiles, trucks, tractors, airplanes and dirigibles, as well as power boats and other marine and river craft, and also railway locomotives.

A further object of my said invention is to provide a crank mechanism which is simple in construction having regard to its merits and advantages, and in which the problem of efficient lubrication is solved in a novel and reliable manner.

With these and other objects in view, I will now describe a preferred embodiment of my invention, reference being had to the accompanying drawings, in which—

Figure 1 is a fragmentary side elevation showing my improved crank mechanism applied to an ordinary bicycle.

Figure 2 is a fragmentary plan view of the same.

Figure 3 is a fragmentary side elevation corresponding to Figure 1, showing a modification of my crank mechanism.

Figure 4 is a fragmentary plan view of the same.

Figure 5 is a fragmentary side elevation corresponding to Figure 1, showing a still further modification of my crank mechanism.

Figure 6 is a fragmentary plan view of the same.

Figure 7 is a fragmentary vertical section, taken in a plane passing through the center line of the crank shaft, showing one form of my improved crank mechanism as applied to a two-cylinder vertical gasoline engine.

Figure 8 is a fragmentary section taken on line 8—8 of Figure 7.

Figure 9 is a diagram illustrating in a general way the operation of my improved crank mechanism.

Figure 10 is a fragmentary sectional view showing an improved method of lubrication employed at the connecting points of the linkages herein described and forming part of my crank mechanism.

Like characters designate corresponding parts throughout the several views.

Referring more particularly to Figures 1 and 2 of the drawings, 1 designates the conventional crank hanger, located as usual at the common intersection of the front brace 11, the center post or saddle support 12, and the rear fork 13, the bifurcations 131 of which are connected to the rear axle of the vehicle in the usual way.

In suitable anti-friction bearings within the crank hanger 1 is supported a crank shaft 2 upon which is keyed the driving sprocket 3 from which the power of the driver is transmitted through the pitch chain 31 to the rear sprocket, not shown, which is connected in driving relation with the rear wheel 32. Adjacent the sprocket wheel and secured to the frame as by screws 41, which threadedly engage bosses 401 upon the said frame, is a plate 4 and to this plate is secured as by screws 51 a cam 5 of the form sometimes described as a triangular eccentric, the said cam having the peculiar property of fitting closely between a pair of parallel surfaces upon an element to be moved during its entire rotation. This cam also imparts to the said element a movement during one fourth of its rotation and then allows the element to rest during another one fourth, after which it gives a reverse movement during one fourth, followed by a rest, and so forth in a continuous cycle.

Keyed to the crank shaft 2 is a crank 6 and arranged at an angle to the said crank is a pedal arm 7 upon which is rotatably mounted a pedal

11 having preferably rubber portions 72 and a central axle 73. The pedal arm 7 has connected to it as by pivots 76, 76' the links 74, 75 which constitute, in combination with the pedal arm 7, 5 a rigid triangular structure, and the pedal arm is further connected by means of the link 77 and the pivot 77' to the extreme end of the crank 6. In this manner the pedal arm 7 is coupled to the crank 6 by a linkage which permits of a 10 certain amount of movement of the said arm in relation to the crank, and the said arm is provided with an opening 78 which is partly defined by a pair of parallel surfaces 79, these surfaces being spaced apart so that they are maintained 15 in operative relation with the cam 5 at all times. Thus, it will be seen that as the arm 7 is rotated by pressure of the operator upon the pedal 71, the effective radius of the pedal is gradually changed during such rotation and the fixed cam 5 is so 20 positioned upon the frame that the pedal is pushed in a forward direction from the center line x-x of the crank hanger just when it passes the said center line, by which means the usual dead center effect of the common crank movement is avoided and the leverage of the pedal 25 is increased at the critical moment when the foot of the operator is in the position to do the maximum amount of work.

The description of my improved mechanism so 30 far relates only to the pedal mechanism on the left side of the operator. It will be understood, however, that the crank mechanism upon the right hand of the operator is similarly constructed with the exception that, since there is 35 no sprocket on this side, the cam 5 is keyed directly upon the outer periphery of the crank hanger itself, thereby dispensing with the fixed plate 4 above referred to. With this exception the parts upon the right hand are similar in all 40 respects to that above described, the various elements being similarly designated. For the sake of clearness, however, the parts upon the right hand are omitted from the elevational view, Figure 1.

45 Referring now to Figures 3 and 4 of the drawings, the pedal arm 7 is connected directly as by the pivot 76' to the crank 6, and instead of the cam 5 described and shown in Figures 1 and 2, there is provided an eccentric 8 which is fastened to the plate 4 as by the screws 81 and is surrounded by an eccentric strap 82, made in two halves and secured together as by the screws 83. The strap 82 is connected by a short arm 84 to the pedal arm 7 as by the pivot 85 so that 50 the effective radius of the pedal is increased during the upper part of the forward rotation in the same manner as is obtained by the cam previously described. The eccentric strap 82 is provided with an oil container 86 closed by a screw cap 87.

55 In Figures 5 and 6 of the drawings I have shown a still further modification of my improved crank mechanism in which the pedal arm 7 is reinforced by members 7', 7'' as shown, so as to provide a triangular brace structure of great rigidity. The pedal arm 7 in this case is connected directly by the pivot 76' to the crank 6, the latter being in this case provided with an extension 61 which is arranged at an angle to the 60 main portion, as shown. With this exception the arrangement is substantially the same as shown in Figures 3 and 4, the eccentric 8 and strap 82 being employed for producing the off center movement of the pedal during the upper portion 65 of its forward stroke. It will be noted that in

Figures 5 and 6 the right hand pedal mechanism only is shown, the left hand elements being omitted for the sake of clearness.

5 In Figures 7 and 8 of the drawings A designates the cylinder block of a two-cylinder four-stroke cycle internal combustion engine, the said block being provided with a head B of ordinary construction and also with a crank case C. D are the compression spaces and E the cylinder bores in which operate pistons F coupled by the usual connecting rods G and wrist pins H to the crank pins K. Within the crank case C, which is split diametrically, as indicated at C', are bearings L of conventional construction within which rotate the various sections of the crank shaft 2. 10

15 The operative elements of the crank mechanism in this application are substantially the same as shown in Figure 1 applied to a bicycle, the several parts being similarly designated. In this case, however, the cams 5 which are arranged in cooperative relation with the arms 7 are formed integral with bushings L', the said bushings being prevented from rotating within the bearings L as by dowel pins L3 and being provided with oil-ways L4. The conventional 20 working parts of the engine such as the valves D' and valve rods D2, cam shaft D3, and tappets D4 need no further description since they 25 form no part of the present invention.

30 In the rough diagram shown in Figure 9 of the drawings I have endeavored to give a general idea of the manner in which my improved crank mechanism obviates the usual dead center condition. Thus by the action of the cam 5 upon the member 7 the crank K which corresponds to the pedal axis in the case of the bicycle application is moved forward approximately fifteen degrees from the vertical center line which would otherwise be occupied by the crank of ordinary construction. The words "crank circle" 35 indicate the circle around which the crank 6 passes while the words "pedal circle" show the total movement of the pedal, which amounts to one hundred and ninety-five degrees at the same time that the crank pin K moves through one 40 hundred and eighty degrees. In this manner the purchase or leverage of the crank pin K is increased by fifteen degrees at the moment when the maximum power is exerted by the foot of the operator in the case of a bicycle, or by the 45 connecting rod in the case of the motor shown in Figures 7 and 8.

50 In the fragmentary drawings, Figure 10, I have illustrated a novel and effective method of lubricating the pivots which connect the various members and links of the mechanisms herein shown and described. Thus the pivot pin designated 76⁴ is secured in the member 75 by a tight or driven fit and welded in position as indicated at 76¹. The portion 76⁴ is rotatable in the member 60 55 74 and is provided with a head 76³ and in order to provide for lubrication of this journal, there may be employed an oil fitting of the "Alemite" type which is arranged to deliver lubricant into an opening 76⁶ so as to provide effective lubrication of the bearing.

65 It will be observed from the foregoing description and by reference to the drawings that I have devised a highly efficient crank movement by which the maximum percentage of the energy 70 input is converted into dynamic effect upon the various instrumentalities to be operated, and while I have herein described and shown a preferred embodiment of my invention, it will be readily understood by those skilled in the art to 75

which the same pertains that various changes in detail may be made without departing from the spirit of my invention as defined in the appended claims.

Having thus described my said invention, what I claim and desire to secure by Letters Patent of the United States is:

1. In a crank movement, the combination, with a fixed bearing, of a driven shaft rotatably mounted in said bearing, a driven crank secured upon said shaft, a cam-like member fixed upon said bearing, a driving arm having at one end a crank pin and at the other end a pivot, a link connecting said pivot in angularly rearward driving relation with said driven crank, and an opening in said driving arm intermediate said crank pin and said pivot adapted to slidably engage said cam-like member, whereby said crank pin is advanced beyond the dead center during the commencement of its forward stroke.

2. In a crank movement, the combination, with a fixed bearing, of a driven shaft rotatably mounted in said bearing, a driven crank secured upon said shaft, a cam-like member fixed upon said bearing, a driving arm having at one end a crank pin and at the other end a pivot, a link connecting said pivot in angularly rearward driving relation with said driven crank, and an opening in said driving arm intermediate said crank pin and said pivot defined by two faces arranged in parallel spaced relation and adapted to slidably engage said cam-like member, whereby said crank pin is advanced beyond the dead center during the commencement of its forward stroke.

3. In a crank movement, the combination, with a fixed bearing, of a driven shaft rotatably mounted in said bearing, a driven crank secured upon said shaft, a triangular cam-like member fixed upon said bearing, a driving arm having at one end a crank pin and at the other end a pivot, a link connecting said pivot in angularly rearward driving relation with said driven crank, and an opening in said driving arm intermediate said crank pin and said pivot defined by two faces arranged in parallel spaced relation and adapted to slidably engage said cam-like member, whereby said crank pin is advanced beyond the dead center during the commencement of its forward stroke.

4. In a crank movement, the combination, with a fixed bearing, of a driven shaft rotatably mounted in said bearing, a driven crank secured upon said shaft, an eccentric member fixed upon said bearing, a driving arm having at one end a crank pin and having the other end pivoted to said driven crank, and a strap upon said eccentric member pivoted to said driving arm intermediate

its ends, whereby said crank pin is advanced beyond the dead center during the commencement of its forward stroke.

5. In a crank movement, the combination, with a bicycle frame, of a fixed bearing upon said frame, a shaft rotatably mounted in said bearing, a pair of driven cranks fixed upon said shaft in diametrically opposed relation, a road wheel upon said frame connected by gearing with said shaft, a pair of cam-like members fixed upon said frame, a pair of driving arms each having at one end a foot pedal and at the other end a pivot, and links connecting said respective pivots to said driven cranks, there being openings in said driving arms adapted to slidably engage said respective cam-like members, whereby said pedals are advanced beyond their dead centers during the commencement of their forward strokes.

6. In a crank movement, the combination, with a fixed bearing, of a driven shaft rotatably mounted in said bearing, a driven crank secured upon said shaft, a cam-like member fixed upon said bearing, a substantially triangular driving structure having at one apex a crank pin and at the opposed apex a pivot, a link connecting said pivot in angularly rearward driving relation with said driven crank, and an opening in said structure intermediate said crank pin and said pivot adapted to slidably engage said cam-like member, whereby said crank pin is advanced beyond the dead center during the commencement of its forward stroke, so that a higher degree of leverage is obtained on the working stroke and a lower degree on the idling stroke and a greater proportion of the dynamic force exerted is utilized in the performance of useful work.

7. In a crank movement, the combination, with a fixed bearing, of a driven shaft rotatably mounted in said bearing, a driven crank secured upon said shaft, a triangular cam-like member fixed upon said bearing, a substantially triangular driving structure having at one apex a crank pin and at the opposed apex a pivot, a link connecting said pivot in angularly rearward driving relation with said driven crank, and an opening in said structure intermediate said crank pin and said pivot adapted to slidably engage said cam-like member, whereby said crank pin is advanced beyond the dead center during the commencement of its forward stroke, so that a higher degree of leverage is obtained on the working stroke and a lower degree on the idling stroke and a greater proportion of the dynamic force exerted is utilized in the performance of useful work.

AMEL B. BROLUSKA.
